No 11,887 July 27, 1880

Cut 211.

UNITED STATES PATENT OFFICE.

OTIS G. CLARK, OF TROY, AND DANIEL D. BUCKLIN, OF LANSINGBURG,
EXECUTORS OF NICHOLAS S. VEDDER, DECEASED, AND FRANCIS
RITCHIE, OF TROY, NEW YORK; SAID RITCHIE ASSIGNOR TO SAID
CLARK AND BUCKLIN AS EXECUTORS.

DESIGN FOR A COOKING-STOVE.

SPECIFICATION forming part of Design No. 11,887, dated July 27, 1880.

Application filed June 14, 1880. Term of patent 3½ years.

To all whom it may concern:

Be it known that NICHOLAS S. VEDDER, deceased, late of the city of Troy, in the county of Rensselaer and State of New York, and 5 FRANCIS RITCHIE, residing in said city, county, and State, did, in the life-time of said NICHOLAS S. VEDDER, jointly invent and produce a certain new and original Design for Cooking-Stoves; and that OTIS G. CLARK, residing in said city of Troy, and DANIEL D. BUCKLIN, residing in Lansingburg, in said county and State, are the executors of the last will and testament of said NICHOLAS S. VEDDER, deceased; and we, the said OTIS G. 10 CLARK, DANIEL D. BUCKLIN, and FRANCIS RITCHIE, do hereby declare the following to be a specification of said new design, reference being had by letters to the accompanying cut, print, or engraving of a cooking-stove having 15 said design.

One part of this invention is the design for the compound panel ornament A, composed of the central cruciform ornament, b, on the ornamental surface c, having the border d, of ornamental outline, with the projecting corner ornaments e, the end ornaments, f, and the side ornaments, g, all shaped and combined so as to present the appearance represented in the accompanying cut.

30 Another part of this invention is the design for the side doors, H I J, the same consisting of the compound ornament A on the panel-surface k, the series of outer border ornaments, l, flaring inward, the inwardly-spreading three-lobed corner ornaments, m, and the inner bor-

der ornamentation, n, all shaped and arranged together, as represented in the aforesaid print.

The design for the front door, O, is composed of the projecting lower section, p, having therein the four rectangular damper-apertures q, with arches r in the middle of the tops, the upper section, s, having the three rectangular illumination-apertures t, with central top arches, u, the inner border-molding, v, and the series of outwardly-flaring ornaments w, all shaped and arranged together as represented in the accompanying engraving.

What is claimed as the joint invention of the aforesaid NICHOLAS S. VEDDER, deceased, and FRANCIS RITCHIE, aforesaid, is—

1. The design for the compound panel ornament A, composed of the parts b, c, d, e, f, and g, all shaped and arranged together as shown and described.

2. The design for the side doors, H, I, and J, consisting of the parts A, k, l, m, and n, all shaped, arranged, and combined as described and shown.

In testimony whereof we hereunto set our hands, in the presence of two subscribing witnesses, this 10th day of June, 1880.

OTIS G. CLARK,
DANIEL D. BUCKLIN,
Executors of Nicholas S. Vedder, deceased.
FRANCIS RITCHIE.

Witnesses:

JAMES A. GILMAN,
CHESTER BASCOM.
